UNITED STATES PATENT OFFICE

104,597

DESIGN FOR A COMBINED SIGN AND CLOCK

Jacob Duman, Chicago, Ill.

Application May 8, 1936, Serial No. 62,539

Term of patent 3½ years

To all whom it may concern:

Be it known that I, Jacob Duman, a citizen of the United States, residing at Chicago, in the county of Cook and State of Illinois, have invented a new, original, and ornamental Design for Combined Sign and Clock, of which the following is a specification, reference being had to the accompanying drawings, forming a part thereof.

In the drawings:

Figure 1 is a front view of a combined sign and clock embodying my design;

Figure 2 is a fragmentary sectional view taken along the line 2—2 on Fig. 1, and showing the stepped back relationship of the various parts; and

Figure 3 is a side elevational view of the disclosure in Figure 1.

I claim:

The ornamental design for a combined sign and clock substantially as shown and described.

JACOB DUMAN.
